Patented Nov. 8, 1927.

UNITED STATES PATENT OFFICE.

AUGUST HUND, OF BETHESDA, MARYLAND, ASSIGNOR TO WIRED RADIO, INC., OF NEW YORK, N. Y., A CORPORATION OF DELAWARE.

CONDENSER TRANSMITTER.

Application filed April 10, 1926. Serial No. 101,203.

My invention relates broadly to voice modulating apparatus and more particularly to a condenser type sound detector and transmitter.

5 One of the objects of my invention is to provide an extremely sensitive sound detector and transmitter for operation in the control circuit of an electron tube amplifier for modulating electrical currents in accordance 10 with sound vibrations.

Another object of my invention is to provide a construction of condenser transmitter in which sound at relatively great distances 15 may be detected and utilized to control the circuit of a condenser transmitter for modulating electrical currents with substantially no distortion.

Another object of my invention is to provide a simplified construction of electro- 20 static transmitter in which a sound distribution plate is provided for uniformly distributing sound vibrations over the area of a relatively flexible plate which may be changed in position by the impinging of 25 sound waves thereagainst for controlling the operation of an electron tube system.

Another object of my invention is to provide an inexpensive construction of condenser transmitter which may be readily manufactured 30 from a relatively small number of parts and yet will have the property of great sensitivity and ability to effectively control the operation of an electron tube system for the production of modulated current in accordance with sound vibrations.

35 My invention will be more clearly understood from the specification hereinafter following by reference to the accompanying drawings wherein:

40 Figure 1 is a front elevation of the condenser transmitter embodying the principles of my invention; Fig. 2 is a cross-sectional view taken through the condenser transmitter on line 2-2 thereof; and Fig. 3 45 shows the electrical connections of the condenser transmitter of my invention with an electron tube system.

Heretofore in the art condenser transmitters have been relatively insensitive as 50 compared with the usual carbon microphone transmitter. Prior constructions of condenser transmitters have been relatively complicated and expensive to manufacture. My condenser transmitter construction is relatively simple and requires only a small

number of parts and yet the device is highly sensitive to sound vibrations and has been used for the detection of very feeble sounds and the modulation of electrical currents in accordance with the sound vibrations. 60

Referring to the drawings in more detail reference character 1 designates one of the end plates constituting one electrode of the condenser transmitter. Reference character 65 2 designates an opposite end plate of the condenser transmitter which is spaced from the plate 1 by means of concentrically positioned insulated ring members 3 and 5, the plates and ring members being secured together by means of bolt members 6 which pass through the several members, the bolts being secured therein by means of nuts which bear upon the insulated bushing members 7, located in the plate member 1. In 70 this manner the plate member 1 is substantially insulated from the plate member 2. A flexible sheet of metal 8 is stretched over the annular flange or bead 4 of the ring member 3 and has its outer periphery 9 75 gripped between the insulated ring members 3 and 5 stretching the sheet 8 in the manner of a drum. The plate 8 is formed of very thin metal foil which is readily moved by sound vibrations impinging thereagainst. 80 The plate 8 forms the other electrode of the condenser detector. The ring member 5 telescopes over the ring member 3 in securing the foil 8 over the bead portion 4. The ring members 3 and 5 fit snugly together in 85 the manner of hoops for clamping the flexible foil 8 therebetween. The plate member 1 is provided with a plurality of apertures represented at 10 positioned throughout the area of plate member 1 which is bounded 90 by the dotted line 11 forming a space or gap 12 immediately over the flexible foil sheet 8.

In Fig. 3 I have shown the electrical connections of the condenser transmitter in an 10 electron tube circuit. The electron tube circuit comprises tubes 14, 15 and 16 in the form of a resistance capacity coupled amplifier whose input circuit is controlled by the condenser transmitter as illustrated. 10 Plate 1 of the condenser transmitter (or detector sensitivity) connects with the grid electrode of the input circuit, while plate 8 connects with the filament electrode of tube 14. A high potential direct current is im- 11

pressed across the electrodes of the condenser transmitter. This potential may be derived from the B-battery source or it may be obtained from an independent source.

5 In the operation of the condenser transmitter the sound enters through the many circular apertures 10 provided in the metallic plate 1. In a preferred embodiment of my invention these apertures have a diameter of about $\frac{1}{16}$ of an inch and their centers are spaced $\frac{1}{8}$ of an inch, that is, their centers are the corners of small squares whose sides is $\frac{1}{8}$ of an inch long. This leaves enough active material in plate 1 for the condenser action and admits the sound very uniformly. In one of my designs I employ an outside diameter of 5" and an effective inside diameter of 4".

20 For the best results I apply about 200 volts across the condenser electrodes for establishing the normal charges on the condenser electrodes. The sound vibrations which impinge upon the flexible foil sheet 8 by passing through the apertures 10 bodily move the flexible sheet 8 for varying the spacial relation between plate 1 and flexible sheet 8 for varying the electrostatic capacity therebetween.

25 The condenser transmitter of my invention has proven so sensitive that I have successfully detected the speech of a person talking in an ordinary tone of voice 150 feet distant from the transmitter. I have detected the disturbances offered by approaching aircraft at a distance of several miles, and other important applications of the invention have been made in instances where the initial sound disturbance is relatively slight, so slight in fact that the ear would normally not perceive such sounds, and yet where positive detection of these slight sounds has been accomplished. Mention may be made herein of the ready adaptability of the invention in the faithful recording of music and voice records, telephone pick-up and devices for assisting the deaf to hear. Many other applications of the invention will readily suggest themselves to those skilled in the art.

30 40 45 50 While I have described my invention in a certain preferred embodiment, I desire it to be understood that modifications may be

made and that no limitations upon the invention are intended other than are imposed by the scope of the appended claims.

55 What I claim as new and desire to secure by Letters Patent of the United States is as follows:

1. A condenser transmitter comprising in combination a pair of insulated ring members, one of said ring members having an annular flange and the other of said ring members fitting around said annular flange in the nature of a hoop, a flexible sheet of metal stretched over said annular flange and gripped between said ring members, and an apertured conductive plate supported by said ring members in spaced relationship to said flexible sheet member for permitting the free passage of sound vibrations to said flexible plate member for varying the electrostatic capacity between said conductive plate member and said flexible plate member.

2. A condenser transmitter comprising in combination a pair of concentrically positioned insulated hoop members fitting one over the other, a sheet of flexible metal stretched over said hoop members forming a drum-like surface, and an apertured metallic plate member secured to said hoop members in spaced relation to said sheet of flexible metal whereby sound vibrations may be directed against said sheet of flexible metal for varying the spacial relation between said apertured plate member and said flexible sheet member.

3. A condenser transmitter comprising in combination a pair of metallic plate members, a pair of insulated rim members telescoped one over the other, and a flexible metallic sheet stretched between said rim members and directly parallel with one of said metallic plate members, said metallic plate members being insulated one from the other and from said flexible metallic sheet, the conductive plate member immediately adjacent said flexible sheet member having means for permitting the impingement of sound vibrations against said flexible sheet member for varying the electrostatic capacity between said conductive plate member and said flexible sheet member.

90 95 100 In testimony whereof I affix my signature.
AUGUST HUND.
